ENDLESS CONVEYER PRESS FOR
FLATTENING BAGS

James J. Shields, Denver, Colo.

Application March 16, 1950, Serial No. 150,050

1 Claim. (Cl. 100—151)

1

This invention relates to a bag flattening machine. Large bags such as used for sugar, salt, flour, cement, etc. are exceedingly unwieldy when first filled due to their round contour. In order to pile, store and handle the bags, it has been found necessary to flatten them so that they will lie flat upon each other without rolling.

The principal object of this invention is to provide a simple and highly efficient machine through which bags of various commodities may be passed and which will act to flatten the bags to provide two flat sides thereon, so as to facilitate piling and stacking.

Another object of the invention is to provide a machine of this character, which will accommodate bags of various sizes without requiring change or adjustment and which will not damage the bags during the flattening process.

A further object is to so construct the device that the amount of pressure placed upon the bags may be regulated to accomplish a maximum flattening action.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved bag flattening machine as it would appear in use.

Fig. 2 is a top plan view thereof; and

Fig. 3 is a detail view illustrating a type of roller employed on the improved bag flattening machine.

The improved bag flattening machine is supported from two side frames 10 and 11 carried on suitable legs 12 and joined by means of cross members 13.

The side frames 10 support a horizontal, fixed conveyor frame 14 extending between the cross members 13 thereon. The fixed conveyor frame 14 is inclined downwardly at its receiving extremity, as shown at 15, and acts to support a plurality of parallel, uniformly-spaced, roller shafts 16.

A grooved roller 17 is mounted on each of the roller shafts 16 and a plurality of elastic, endless belts 18 extend between the grooves of the adjacent rollers 17 in staggered relation as shown in Fig. 2. One of the roller shafts, herein designated

as the drive shaft 19, is fixed to its roller 17 and is driven from an electric motor 20, through the medium of a drive belt or chain 21, so as to cause the upper reaches of the belts 18 to travel to the left in Fig. 1.

A floating conveyor frame 22 is swingingly suspended above the fixed conveyor frame 14 upon swinging links 23, extending from cross shafts 24, supported between the side frames 10 and 11. The floating conveyor frame 22 is also provided with a plurality of roller shafts 25, each of which carries one of the grooved rollers 17. It is also provided with a drive-shaft 26, which is rotated from a second electric motor 27, through the medium of a drive belt or chain 28. The second electric motor is mounted on a baseboard 29 extending between and supported by the sides of the floating conveyor frame 22. The receiving extremity of the floating conveyor frame 22 is inclined upwardly as shown at 30.

One pair of the links 23 is fixed to one of the shafts 24 so that the movement of the links is transmitted to the shaft. This shaft is provided with an upwardly extending lever 31, which is constantly urged to the left in Fig. 1 by means of a tension spring 32. The spring 32 extends from the lever 31 to a threaded eye bolt 33 extending through the upper portion of one of the legs 12. A nut 34 is threaded on the bolt 33 and arranged to be rotated by means of a crank 35.

It can be readily seen that if the nut 34 is tightened, the spring 32 will be tensioned so as to increase the downward pressure of the floating frame 22. The amount of downward movement of the floating frame can be limited by means of a stop pin 36, which is insertable through any desired hole in a perforated sector member 37 mounted on the frame 10 in the path of movement of the lever 31.

The bags to be flattened, indicated at 38, are fed onto the inclined receiving extremity 15 of the fixed conveyor frame 14 in any suitable manner, such as from a delivery conveyor 39. The bags are carried forwardly by being gripped by the travelling belts 18 and 40 and are forced between the two conveyors. The rollers 17 exert a kneading action on the bags under the influence of the weight of the floating conveyor 22 so that they are brought to a uniform flattened condition as they pass between the two conveyors without packing the contents. The flattening action can be increased by tightening the nut 34.

If bags of a uniform size are being continuously passed through the flattening machine, it is un-

necessary to allow the floating conveyor to swing completely downward after each bag passes since the downward motion may be stopped at any desired point by means of the stop pin 36. The belts 18 may be formed from any suitable material. It is preferred, however, to form them from coiled wire springs, as illustrated, so that they will constantly maintain themselves tight and yet will assert a yielding action upon the passing bag. They could, if desired, be formed from resilient tread stock rubber or "neoprene" so that they may be stretched over the rollers.

While a specific form of the improvement has been described and illustrated herein, it is to be understood that the same may be varied, within the scope of the appended claim, without departing from the spirit of the invention.

Having thus described the invention, what is claimed and desired secured by Letters Patent is:

A bag flattening device comprising: two spaced-apart rigid side frames; a horizontal, fixed conveyor frame supported between said side frames, said side frames extending above said fixed conveyor frame; said fixed conveyor frame having a downwardly inclined receiving extremity; conveyor elements supported throughout the length of said fixed conveyor frame; a plurality of cross shafts supported by said side frames transversally of said fixed conveyor frame and above the latter; a pair of links swingingly depending from such cross shaft; a floating conveyor frame suspended from said links over said

fixed frame so that the former may swing longitudinally of the latter; said floating conveyor frame having an upwardly inclined receiving extremity; conveyor elements carried throughout the length of said floating conveyor frame; a first motor carried by and movable with said floating frame and operatively connected to the conveyor elements thereof; a second motor carried by said fixed frame and operatively connected to the conveyor elements of the latter; a lever secured to and extending upwardly from one of said shafts, the links depending from the latter shaft being secured thereto so that the swinging action of said links will be communicated through said shaft to said lever; and a tension spring secured to and extending from said lever to one of said side frames to resist swinging movement of said lever in one direction.
